INVENTOR:

Charles Reinisch

BY Campbell & Co. ATTYS

UNITED STATES PATENT OFFICE.

CHARLES REINISCH, OF NEWARK, NEW JERSEY.

BAG-LOCK.

SPECIFICATION forming part of Letters Patent No. 402,769, dated May 7, 1889.

Application filed April 20, 1888. Serial No. 271,317. (No model.)

To all whom it may concern:

Be it known that I, CHARLES REINISCH, a citizen of the United States, residing at Newark, in the county of Essex and State of New Jersey, have invented certain new and useful Improvements in Bag-Locks; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

15 In the sheet of drawings herewith accompanying is illustrated my invention, which relates to improvements in bag fastenings and locks, the purpose of which is to provide a strong fastening of simple and cheap construction, and which can readily be used either for inside or outside locks.

20 In said drawings, in which similar letters of reference indicate corresponding parts in each of the views, is shown my improved fastening arranged as an inside lock on what is known as an "English" frame, Figure 1 of said views representing a front elevation of the fastening and a portion of the frame to which it is secured. Figs. 2 and 3 are plan 25 views of the top and inside of the fastening, respectively. Figs. 4, 5, and 6 are longitudinal sections taken centrally through the fastening in its fastened and unfastened positions, respectively. Fig. 7 is a similar view 30 indicating the locked position of the finger-piece. Fig. 8 is a perspective view of the slotted collar detached from the finger-piece, and Fig. 9 is a perspective view of the collar employed in the locking mechanism.

35 In said above-mentioned views, A and B indicate the portions of the bag-frame shown therein; a, the main part of the casing in which the operative elements of the fastening are arranged; a', the removable top plate, and a² ears or flanges by which said casing is attached to the portion A of the frame. Sliding within said casing are bolt-40 plates c and c', having bolts or projections c² and c³ thereon, and inclined or beveled surfaces c⁴ and c⁵, which are arranged contiguously to one another. Springs d and d'

are placed between said bolt-plates and the ends of the casing, and act to hold the bolts c² and c³ across the loop-perforations a³ in the casing, and also maintain the engagement of the inclined surfaces on the bolt-plates 55 with the beveled surfaces on the base of the finger-piece. To the opposite frame-section, B, is screwed the loop-plate b, from which projects catching-loops b' b², which enter 60 openings a³ in the casing and engage with the bolts, as indicated in Fig. 3.

The finger-piece consists of a base, e, having beveled surfaces e' and e², which engage with the inclined surfaces c⁴ and c⁵ on the 65 bolt-plates, and rising from said base and projecting through the casing, and also through the top of the frame, when used as an inside lock, is the chambered or hollow finger-piece proper, e³, in the top of which is 70 the key-hole e⁴. Below the key-hole is a chamber having a slot, f, extending therethrough, and shorter slots, f' and f², in the bottom of said chamber. Directly beneath said chamber is a pin, g, around which turns a collar, 75 g', Fig. 9, provided with points g² and g³ thereon, which correspond in position and enter the slots f' and f² on the interior of the chambered finger-piece. The number and position of said slots f' and f² and the points 80 g² and g³ may vary as desired, although two of each are considered preferable. The said slots on the interior of the hollow finger-piece can be cut in the interior wall thereof, as will be understood, or the same can be cut in a 85 separate cylinder, g⁴. (Shown in detail in Fig. 8 and in other views of the drawings.)

By depressing the finger-piece the engagement of the beveled surfaces on the base of said finger-piece and the bolt-plates causes 90 said plates to move oppositely toward the ends of the casing, thereby drawing the bolts out of the catching-loops, as shown in Fig. 6. Upon the release of the finger-piece the springs return the plates and finger-piece to 95 their normal positions. (Shown in Figs. 4 and 5.)

As long as the points g³ and g⁴ on the collar are directly beneath the slots f' and f² in the chamber of the finger-piece, as shown in 100 Fig. 5, the said piece can be depressed, as indicated in Fig. 6, because the points can

enter said slots; but when said collar is turned by the key so that said points with which said key engages are turned away from beneath said slots the engagement of the points 5 with the solid or uncut bottom of the chamber prevents any depression of the finger-piece, and thereby locks the fastening. This locked position is illustrated in Fig. 7.

When the fastening is used on the outside 10 of the bag-frame, instead of the inside thereof, as shown in the drawings, the portion e^3 of the finger-piece may be made much shorter than as shown in the drawings, as will be understood by those acquainted with the art.

Having thus set forth my invention, what 15 I claim is—

1. A bag-fastening consisting of a casing provided with catching-loop-receiving openings therein, catching-loops adapted to enter 20 the openings in said casing and to engage with bolts arranged therein, independently-arranged sliding bolts moving reciprocally within the casing across the loop-openings therein and attached to sliding plates having 25 inclined surfaces thereon, a finger-piece provided with a beveled surface or surfaces thereon which engage with the inclined surfaces on the bolt-plates when said finger-piece is operated, to cause the disengagement 30 of the bolts and catching-loops, and springs arranged to cause the return of the bolts to their normal position across the loop-openings in the casing, for the purposes set forth.

2. A bag-fastening consisting of a casing 35 having openings a^3 therein, catching-loops b' and b^2 , which enter said openings and engage with sliding bolts in the casing, bolts c^2 and c^3 , moving reciprocally in said casing across the openings and secured to bolt-plates c and 40 c' , and having inclined surfaces c^4 and c^5 thereon, a finger-piece projecting up through

the casing and provided with beveled surfaces on the lower end thereof, which engage with the inclined surfaces on the bolt-plates, and springs d and d' , arranged to cause the 45 return of said bolts to their normal position, substantially as and for the purposes set forth.

3. In a bag-fastening, a locking device consisting of a hollow cylinder provided with a slot, f , and slots f' and f^2 on the inside thereof 50 and formed substantially as herein set forth, a collar, g' , provided with pins or points g^2 and g^3 , and a pin, g , about which said collar turns, for the purposes set forth.

4. A combined bag fastening and lock, consisting of a casing having openings a^3 therein, catching-loops b' b^2 , which enter said openings and engage with sliding bolts arranged in said casing, bolts c^2 and c^3 , moving in said casing across said openings and secured to 60 bolt-plates c and c' , having inclined surfaces c^4 and c^5 thereon, a finger-piece, e^3 , projecting up through the casing and provided with beveled surfaces on the lower end thereof, which engage with the inclined surfaces on the sliding bolts, springs d and d' , arranged to cause the 65 return of said bolts to their normal position, said finger-piece being hollow and provided with a key-hole on the top thereof and slots f' and f^2 , a collar provided with points 70 or projections g^2 and g^3 thereon, and a pin, g , about which said collar turns, all of said parts being arranged substantially as and for the purposes set forth.

In testimony that I claim the invention set 75 forth above I have hereunto set my hand this 16th day of April, 1888.

CHARLES REINISH.
